[57]

The ornamental design for body cavity sealing means for fowl eviscerating device, as shown and described.

DESCRIPTION

FIG. 1 is a side elevational view of a body cavity sealing means for fowl eviscerating device showing my new design.

FIG. 2 is a top plan view thereof.

FIG. 3 is a bottom view thereof.

FIG. 4 is a front elevational view thereof.

FIG. 5 is a rear elevational view

The broken line disclosure of the vacuum tubes in FIG. 1 is for illustrative purposes only and forms no part of the claimed design.
